UNITED STATES PATENT OFFICE

2,601,438

PAINT STIRRER ATTACHMENT FOR CANS

Walfred Johnson, Racine, Wis.

Application February 2, 1950, Serial No. 141,868

2 Claims. (Cl. 220—85)

1

My invention refers to self-contained stirring paddles for canned liquids.

The object of my invention is to provide a metallic paddle flatly attached to a can, comprising a strip reinforced by a central rib forming a handle extension for the major portion of the length of the strip. The upper end of the handle terminates with a hook, and the lower end portion with an S-shaped offset shoulder, having extending therefrom a flat yieldable stirring blade, whereby paint or other fluid products may be thoroughly mixed for use.

The stirring paddle handle, when not in use, is firmly secured to the outside wall of the can by seating the hooked end over the top bead of said can, and thereafter snapping the S-shaped shoulder over the bottom can bead and finally folding the blade flatly against the bottom can head, whereby the paddle is snugly anchored to the can in such manner that groups of cans may be nested in shipment without forming interfering projections.

In practice, it is contemplated to initially bow the blade, whereby it is pressed by a plug tool or by hand flatly against the can head bottom.

It is also understood that these stirring paddles may be separately supplied to dealers for retail purchase in which case they are supplied to cans in stock, such as paint or other fluid products that may require thorough mixing before use.

With the above and other objects in view, which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:

Figure 1 represents a partly sectional elevation of a can having a stirring paddle attached thereto, embodying the features of my invention.

Figure 2 is a side elevation of the stirring paddle distended in its position of use.

Figure 3 is a face view of the same.

Figure 4 is a cross section of the paddle, the section being indicated by line 4, 4 of Figure 3.

Figure 5 is another cross section of the paddle,

2

the section being indicated by line 5, 5 of Figure 3.

Figure 6 is a sectional elevation of a can illustrating in full and dotted lines the stirring paddle in various positions for mixing the fluid contents of a can.

Figure 7 is a similar view illustrating another mixing position of the stirring paddle; and

Figure 8 is a fragmentary detailed sectional elevation of the bottom corner of a can illustrating a fragment of the blade and of the paddle slightly bowed before the same is pressed against the bottom head of the can.

Referring by characters to the drawings, A indicates a can body having a top bead B and a slip cover C, the bottom of the can being provided with a bead D and a bottom head E, all of which are of standard type. Mounted flatly against the can body is a metallic strip comprising a handle portion I formed with a central reinforcing rib I'.

The upper end of the handle is folded inwardly to form a hook 2, which hook engages the top bead of the can, and at the lower end of the handle portion the strip is formed with an inwardly extended S-shaped shoulder 3, which shoulder engages the lower can bead D. The paddle is completed by a flat stirring blade 4 which extends from S-shaped shoulder, and when the stirring paddle is attached to the can, as shown in Figure 1 of the drawing, the blade 4 is folded flatly against the bottom face of the can head E. Thus, it will be noted that the stirring paddle is firmly attached to the can and may readily be transported therewith, as shown in Figure 1 of the drawings.

When it is desired to utilize the stirring paddle for mixing paint or other fluid contained in the can, it is removed therefrom, and as shown in Figures 2, 3, 6 and 7, the blade portion is then straightened out in alignment with the handle, whereby it will serve as a flexible fluid mixing unit.

Thus, when it is inserted in a can for mixing, the blade portion will perform a general stirring operation in conjunction with the lower portion of the handle, whereby the bottom and sides of the can may be thoroughly scraped and the contents agitated, and also the offset shoulder portion of the paddle will permit lifting of the fluid contents of the can while, at the same time, the said shoulder may be conveniently inserted under the corner of the upper can bead, whereby the paddle will thus thoroughly scrape and agitate the paint or other fluid before it is put to use, and crude mixing sticks or the like may be eliminated.

As shown in Figure 8 of the drawings, when a paddle is to be attached to the body of a can for convenience, the blade portion 4 is previously bowed, hence, it may readily be flattened down upon the bottom face of the can by any suitable instrument or by hand, whereby it will, due to its flexure, firmly seat in its proper flat position.

While these novel paddles may be shipped attached to cans, it is apparent that I may, in some instances, distribute them to dealers for use, whereby they may be purchased and attached to cans in stock.

I claim:

1. In a paint can or the like of the type having a marginal bead at each end, an attachment therefore serving as a means for mixing and agitating the contents, said attachment comprising a metallic strip adapted to closely conform to the contour of the can body and to detachably engage said marginal beads, said strip including a handle portion extending substantially the length of the can and having one end terminating in a hook engaging one of said beads, a U-shaped portion integral with the opposite end of said handle for engaging the other bead, and a paddle blade extending transversely of said handle portion and adapted to closely engage the respective end of the can.

2. In a paint can or the like of the type having top and bottom marginal beads, an attachment therefor serving as a means for mixing and agi-

tating the contents comprising a bendable metallic strip so constructed and arranged as to closely conform to the contour of the can body and to detachably engage over said marginal beads, said metallic strip including a handle having its major portion provided with a strengthening rib and terminating at its upper end in a hook adapted to engage the top bead of the can, a U-shaped portion integral with the lower end of said handle and adapted to engage over the bottom bead, and a paddle blade secured to said U-shaped portion extending transversely of the handle and lying in close proximity to the can bottom, said paddle blade being bendable downwardly to lie in a vertical plane substantially parallel to the vertical plane of said handle whereby upon removal of said attachment from the can the contents thereof may be thoroughly mixed.

WALFRED JOHNSON.
